CONTAINER FOR COLORING AGENT CAPSULES

Filed March 29, 1922

Inventor
A. English.

By *Franklin D. English* Attorney

UNITED STATES PATENT OFFICE.

ARTHUR ENGLISH, OF KANKAKEE, ILLINOIS.

CONTAINER FOR COLORING-AGENT CAPSULES.

Application filed March 29, 1922. Serial No. 547,764.

To all whom it may concern:

Be it known that I, ARTHUR ENGLISH, a citizen of the United States, residing at Kankakee, in the county of Kankakee and State of Illinois, have invented certain new and useful Improvements in a Container for Coloring-Agent Capsules; and I do hereby declare the following to be a full, clear, and exact description of the invention, such as will enable others skilled in the art to which it appertains to make and use the same.

This invention relates to a container for capsules or the like containing a coloring agent such as is sold or provided with packages of margarine or artificial butter and the like and for admixture of the coloring agent therewith.

The prime object is to provide a means which will positively avoid indentation of the butter with the fingers as by the sales clerk in order to accommodate the capsules within the butter substitute carton or package at the time of sale and which is the present practice, and to provide a means which will positively overcome the contact of the fingers of the sales clerk or other person with the artificial butter at any time before it reaches the consumer in order to thus materially aid in its sanitary handling or marketing.

Another important object is to provide a container which is attachable to a box or carton which contains the artificial butter, which container has a depression to enter the butter to assist in anchoring the same in place and in which depression the capsule is insertible through an opening in the wall of the box or carton preferably closed by a bendable flap.

Still another important object is to provide the container of such construction that it may be made from a single piece of bendable metal or other material to enable its rapid and expeditious manufacture at minimum cost.

Additional objects and advantages will become apparent from a consideration of the description following taken in connection with accompanying drawings illustrating a practical embodiment.

In said drawings:—

Figure 1 is a perspective view showing a carton adapted to contain artificial butter having my improved container in place thereon with the closure flap thereof in open

position and with its closed position suggested in dotted lines;

Figure 2 is a longitudinal sectional view through a carton containing artificial butter and with my improved container in place; indented into the butter and retaining a capsule bearing a coloring agent, and

Figure 3 is a detail perspective view of the container alone and with its flap open.

Like reference characters designate like or similar parts in the different views.

Referring specifically to the drawings, a box or carton, for instance of pasteboard as usual, is shown at A which contains for example margarine or artificial butter at B in block form as usual. The carton A has one of its walls as a movable end closure C.

As is usual, a pill or capsule D of any suitable form for instance a gelatinous globule and adapted to contain a liquid coloring agent for admixture with the margarine B by the consumer is sold or presented to the customer with the package. In this instance, a novel container at E is provided for the capsule D.

The said container E is adapted to be stamped in a single piece from a sheet of bendable metal or other material and it has the closure tab at 10, a depression or receptacle at 11 and a flange at 12 surrounding the said receptacle 11.

To accommodate the use of the container E, one wall of the carton or box A, preferably the closure wall or flap C is provided with a slit at 13 and with an insert opening 14 relatively close thereto.

When the article B is sold, the receptacle E may be in place with the closure flap 10 passed through the slit 13 to slide against the exterior of the wall C while the flange 12 rests against the inner surface of the wall C and the receptacle 11 is depressed into the artificial butter B. The depression of the receptacle 11 into the butter in the manner mentioned, will tend to prevent displacement of the container E, particularly in the plane of the wall C. When the package is sold, the capsule D may be inserted through the opening 14 and into the receptacle 11 after which the tab 10 is bent over the opening 14 in order to close the same. If desired, before the package is sold to the retailer, the capsule D may be disposed within the receptacle 7 as will be understood.

As a result of the improvement, the arti-

ficial butter B will not have to be touched by the sales clerk or anyone prior to its reaching the consumer. Accordingly, the present prevalent practice of the sales clerk 5 pressing his finger directly into the artificial butter to provide a cavity into which he places the capsule D, is overcome. Hence, the artificial butter or equivalent material may be handled in a thoroughly sanitary 10 manner.

As merely one practical embodiment of the invention has been illustrated and described, it is to be understood that changes in the details may be resorted to provided 15 they fall within the spirit and scope of the invention.

I claim as my invention:—

1. In combination with a carton and its 20 contents, a container positioned by the carton having a receptacle deppressible into the contents of the carton, a closure flap on the container projecting through the carton and disposed in closing relation with the receptacle, and the carton having an opening 25 to permit access to the receptacle and adapted to be closed by said flap.

2. A container for attachment to a carton 30 consisting of a single blank for passage through the wall of the carton, the blank being bendable intermediate its ends to form a flap on one side of the wall, the blank having a depressed receptacle on the other side of the wall extending away from and to be closed by the flap.

3. A container for attachment to a carton 35 adapted to be passed through the wall of the carton, the container being bendable intermediate its ends to form a flap on one

side of the wall and a portion substantially parallel with the flap on the other side of the wall, and a receptacle accessible through said wall and extending from said portion and away from said wall.

4. A container for attachment to a carton 40 adapted to be passed through the wall of the carton, the container being bendable intermediate its ends to form a flap on one side of the wall and a portion substantially parallel with the flap on the other side of the wall, a receptacle accessible through said 45 wall and extending from said portion and away from said wall, and said wall being a closure for the carton.

5. A carton having a container extending 50 through the wall, the container having a portion overlapping the exterior of the wall and a portion overlapping the interior of the wall and the latter portion having a receptacle extending away from said wall and the first mentioned portion.

6. A carton having a container extending 55 through the wall, the container having a portion overlapping the exterior of the wall and a portion overlapping the interior of the wall and the latter portion having a receptacle extending away from said wall and the first mentioned portion, said wall having an opening therethrough to permit access to the receptacle, and the first mentioned portion constituting a closure for said opening.

In testimony whereof I affix my signature in presence of two witnesses.

ARTHUR ENGLISH.
